UNITED STATES PATENT OFFICE.

ARVEL T. SINK, OF DETROIT, MICHIGAN, AND GEORGE A. DUDLEY, OF BUFFALO, NEW YORK.

MILLING-MACHINE.

1,137,917.

Specification of Letters Patent.

Patented May 4, 1915.

Application filed May 20, 1914. Serial No. 839,683.

To all whom it may concern:

Be it known that we, ARVEL T. SINK and GEORGE A. DUDLEY, citizens of the United States, residing at Detroit, county of Wayne, State of Michigan, and Buffalo, county of Erie, State of New York, respectively, have invented a certain new and useful Improvement in Milling-Machines, and declare the following to be a full, clear, and exact description of the same, such as will enable others skilled in the art to which it pertains to make and use the same, reference being had to the accompanying drawings, which form a part of this specification.

15 This invention relates to milling machines and more especially to milling machines for turning crank pins.

In the drawings,—Figure 1, is an end view of the machine with a part of one gear-housing broken away. Fig. 2, is a longitudinal vertical section taken on the line A—A of Fig. 1. Fig. 3, is a top or plan view of the main part of the machine. Fig. 4, is a front elevation, a part of one gear-housing 25 being broken away.

The bed *a* of the machine is a casting supported at the ends by uprights *b*. The back of the machine is inclosed by the web *c* which connects the uprights *b*, *b* and also 30 forms a support for the bed *a*. The uprights and web *c* rest upon the base *d*. At the front of the machine is a vertically movable frame *e*. This frame *e* is provided with a pair of internally threaded legs *f*. The 35 rotatable screwthreaded posts *g* engage with the threads of these legs. These screwthreaded posts are rotated at a low speed by reason of the helical gears *h* engaging with the worm gears *i* upon the countershaft *j*.

40 This countershaft *j* is connectible with the pulley wheel *k* by the shiftable clutch head *l* operable by the lever *m*. This clutch head *l* may also be shifted to connect with the pulley wheel *n*. These pulley wheels run in 45 opposite directions by reason of one of the belts being crossed between the pulley wheel and the power shaft *o*. This power shaft *o* is supported by integral brackets *p* protruding outwardly from the web *c*. At the left 50 hand end of the power shaft are several pulleys *q* whereby different speeds and disconnection of the power can be effected. Intermediate the two ends of the power shaft *o* are a plurality of pulley wheels *r* which are 55 used to drive the operating tools of the ma-

chine. These tools are spiral end mills *s*, that is, cutters in the form of cylinders with spirally arranged cutting edges on the periphery and cutting edges on the ends. The shank *t* of the tool is provided with a pair 60 of collars *u*. An externally threaded sleeve *v* surrounds the shank between the two collars *u*, *u*. This sleeve *v* is mounted in a pair of tubular bearings *w*, *w* between which is a spanner nut *x*. The screw *y* protruding into 65 the longitudinal groove *z* of the sleeve *v* constrains the sleeve and the tool to move longitudinally when the spanner nut *x* is turned. This arrangement allows a micrometer adjustment of the tool with respect to 70 the work.

As already explained, the rotative movement of the shank *t* is derived from the pulley wheels *r*. The small pulleys *l* on the ends of the shank are connected by the belts 75 2 with these pulley wheels *r*. Inasmuch as the pulleys *r* are fairly large and the pulleys *l* are small, the end mills are revolved very rapidly. Examining the power connections between the power shaft and the 80 rotatable threaded posts *g*, it will be seen that the power is considerably reduced. Hence the frame *e* does not move vertically very rapidly.

The frame *e* slides vertically on the tracks 85 3 upon the front and sides of the uprights *b*. The frame *e* carries a pair of gear-housings 4. On the posts 5 at the ends of the frame are journaled, one at each end, the pulley wheels 6. Each of these carries a smaller 90 beveled gear 7 with which the beveled pinion on the end of the shaft 8 meshes. A worm 9 on the opposite end of the shaft 8 meshes with the helical gear 10 which is connected by a short shaft with the head-stock 11. 95 Belts 12 connect the pulley wheels 6 with the power shaft *o*. It will be noticed by following these power connections through that there is a considerable reduction in the speed of rotation from the power shaft to the 100 head-stock. Work clamps 14 are located on the face of the head-stocks 11 and these clamp the ends of the work—the plural-throw crank shaft 15.

The two tools shown in the drawings are 105 each mounted upon a carriage 16. This carriage 16 may be adjusted longitudinally of the bed by loosening the nuts 17 which engage with screws, whose heads are held in the longitudinal grooves 18, that have con- 110

stricted openings. The tools may be easily moved toward or from the work by reason of the carriages 16 being mounted upon the upper or movable bed 19. This upper or movable bed can slide crosswise of the stationary bed *a*. The stationary bed *a* is provided with tracks in the form of tenons 20 of a dove-tail. The upper or movable bed is provided with half a dove-tail recess for each tenon. The other half of the dove-tail recess is formed by the longitudinally movable blocks 21 which are moved into or out of engagement with the tenons or tracks 20 by the right and left screw-threaded rod 22 which may be rotated by the crank handle 23. These blocks may be brought into such firm engagement with the tenons as to practically lock the upper bed in any position of adjustment with the lower bed *a*. The movement of the upper bed 19 is effected by turning the crank handle 24 that connects with the rod 25. This rod 25 is journaled in a pair of depending lugs 26 which are integral with the stationary bed *a*. The pinion 27 on the end of the rod 25 meshes with the idler pinion 28 which in turn meshes with the rack 29 on the bottom of the upper bed 19. The idler serves to make the bed move the way the crank turns.

30 The operation of the machine is as follows: The work 15 is inserted between the clamps 14 of the head-stocks 11. These clamps 14 are set eccentrically upon the head-stock so as to bring two pins of the 35 crank shaft to a position of centricity with respect to the head-stocks. The pins undergoing the machining are therefore merely rotated upon their own axes to successively present new portions to the cutting edge of 40 the end mills *s*. In the meantime, the frame *e* moves upward to bring the pins undergoing machining across the end mill so as to bite into the work. The movement of the table may be reversed by throwing the clutch 45 lever *m* into the other clutch part.

As already explained, by turning the spanner nuts *x* the position of the end mills with respect to the carriages 16 may be minutely changed. This will allow the careful adjustment of each end mill with respect 50 to each crank pin after the movable bed has been adjusted. An arm 31 and a screw 30 engaging with the rear of the stationary bed *a* limit the amount of approach of the mill 55 ends to the work that is possible.

What we claim is:

1. In a milling machine, the combination of an end mill, means for holding a crank shaft eccentrically of one of the crank pins, 60 means for revolving the said crank shaft so as to rotate the said crank pin upon its axis, and means for moving the crank shaft across the end mill in a direction crosswise of the axis of rotation.
- 65 2. In a milling machine, the combination

of a rotatable end mill, head stocks, means upon the head stocks for holding a crank shaft eccentrically thereof to bring the crank pin adjacent the end mill in concentric relation with respect to the head stock, means for rotating the head stock, and means for moving the head stock to cause the work to cross the end mill crosswise of the axis of rotation.

3. In a milling machine, the combination 75 of an end mill, means for holding and rotating the work adjacent the end mill, means for causing the work to move across the end mill perpendicular to the axis of rotation, a movable bed, a stationary bed, means for adjusting the movable bed along the stationary bed, and a carrier for said end mill adjustable longitudinally of the movable bed and perpendicular to the direction of movability 80 of the movable bed.

4. In a milling machine, the combination of an end mill, means for holding and rotating the work continuously and automatically, a bed upon which the end mill is mounted, a frame upon which the means for holding and rotating the work is mounted, the said frame being slidable vertically with respect to said bed, and automatic means for slowly sliding said frame vertically to carry the rotating work across the end of the end 95 mill.

5. In a milling machine, the combination of a rotatable end mill, a head stock for holding and rotating the work, flexible driving connection for said head stock, a bed 100 upon which said end mill is mounted, a frame having a sliding connection with the bed and upon which the head stock is mounted, said frame provided with a leg that is threaded, a screw in the form of a 105 rotatable post engaging with said leg, a helical gear on said screw, and a worm for driving said helical gear.

6. In a milling machine, the combination 110 of a rotatable end mill, a carriage for holding said end mill, a longitudinal grooved movable bed, said groove of the movable bed having a constricted opening, a bolt having a head within said groove and passing through said carriage, a nut screwing onto 115 the end of the bolt, and a stationary bed having a track engaging with a complementary recess in the movable bed, said track and recess being arranged so that the travel of the movable bed is across the stationary bed and at right angles to the adjustable path of the carrier upon the movable bed.

7. In a milling machine, the combination 125 of a rotatable end mill, a carriage therefor, a movable bed, means for adjusting the carriage longitudinally of the movable bed, a stationary bed provided with a tenon-like track running crosswise the movable bed, the said movable bed being provided with a half 130

dove-tailed recess, a block and a screw for forcing the block against one side of the tenon-like track to complete the dove-tailed recess.

5 8. In a milling machine, the combination of a pair of rotatable end mills, separate carriages for each end mill, a movable bed across which said carriages are adjustable longitudinally parallel with the work, automatic means for holding and continuously rotating the work, a stationary bed, means for adjusting the movable bed crosswise of the stationary bed and toward or from the work, a frame vertically movable with respect to the movable bed and upon which is mounted the automatic means for holding and rotating the work, means for slowly moving said frame upward and downward, and means by which the power may be reversed to determine the direction of the vertical movement of the frame.

9. In a milling machine, an end mill, a pair of tubular bearings through which said end mill passes a nut between the tubular bearings, the said end mill being provided with a shank having a pair of collars, one on the outside of each tubular bearing, a

threaded sleeve between said collars and passing through said tubular bearings and the nut, the said threaded sleeve being provided with a longitudinal groove, and a screw or projection passing through one of the tubular bearings into the said longitudinal groove.

10 10. In a milling machine, the combination of a rotatable end mill, a carriage for said end mill, a movable bed upon which said carriage is adjustable parallel with the work, a stationary bed upon which said movable bed may be adjusted toward or from the work, and an arm passing from said movable bed to the rear and provided with an adjustable set screw to limit the approach of the end mill to the work.

In testimony whereof, we sign this specification in the presence of two witnesses.
